UNITED STATES PATENT OFFICE.

GEORGE S. HILL, OF STRAFFORD, NEW HAMPSHIRE, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,276,358.

Specification of Letters Patent. Patented Aug. 20, 1918.

Application filed August 28, 1916. Serial No. 117,241.

To all whom it may concern:

Be it known that I, GEORGE S. HILL, a citizen of the United States, residing at Strafford, in the county of Strafford and State of New Hampshire, have invented certain new and useful Improvements in Sewing-Machines; and I do hereby declare the following to be a full, clear, and exact description of the invention, such as will enable others skilled in the art to which it appertains to make and use the same.

The invention relates to machines for sewing overseams.

The object of the invention is to provide novel and improved looper and loop spreader mechanism for coöperating with the vertically reciprocating needle or needles of the sewing mechanism, which will operate in a uniformly reliable manner, and which is well adapted for high speed operation. To this end the invention comprises the features of construction and combinations of parts hereinafter described and referred to in the claims, the advantages of which will be apparent to those skilled in the art from the following detailed description of the mechanisms shown in the accompanying drawings which embody the preferred form of the invention.

In the drawings, Figure 1 is a sectional elevation showing so much of a buttonhole sewing machine as is necessary to illustrate the application of the present invention thereto; Fig. 2 is a partial transverse sectional elevation on line 2, Fig. 1; Fig. 3 is a detail plan view of the turret which carries the under sewing mechanism; Fig. 4 is a sectional elevation on line 4, Fig. 3; and Figs. 5 to 15 are views showing the mode of operation in forming the overseam stitches, Fig. 7 being a sectional view taken on line 7, Fig. 5, Fig. 8 being a sectional view taken on line 8, Fig. 6, and Fig. 15 being a sectional view taken on line 15, Fig. 14.

In the drawings the invention is shown as embodied in a buttonhole making machine having the same general construction and mode of operation as the machine shown and described in application Serial No. 104,449, filed June 19, 1916. The machine comprises in general a cutter which operates to cut the buttonhole slit after the completion of the sewing, a reciprocating and laterally moving work clamp, and a sewing

mechanism which is rotated during the sewing about the eye of the buttonhole, and which comprises a vertically reciprocating and laterally vibrating or jogging upper needle and coöperating looping and loop spreading devices arranged below the work and including a thread carrying looper.

In the machine shown the work clamps, indicated at 2, are mounted upon work supporting plates 4, which are pivoted on a longitudinally and laterally moving clamp carriage 6. The clamps are automatically closed at the beginning of the sewing, and are automatically opened after the completion of the buttonhole, by mechanism which forms no part of the present invention, and which need not be described. The buttonhole slit is cut after the completion of the sewing by a cutter 8 operated by a cam on the main cam shaft of the machine. The work is carried by the clamp over a throat plate 10 mounted upon the turret 12 which carries the under looping and loop spreading mechanism.

In the embodiment of the invention shown the sewing mechanism is adapted to form the well-known Humphrey stitch, and comprises a vertically reciprocating and laterally jogging upper needle 14, and two opposed looper points 16 and 18 arranged to reciprocate below the throat plate and to alternately enter loops thrown out by the needle during its successive reciprocations. The looper point 18 is constructed to take a loop of needle thread and carry it forward into position for the passage of the needle therethrough during its next reciprocation. This looper, after it has taken the loop of needle thread, is moved laterally, and to insure the proper spreading and positioning of the loop of needle thread, a thread retaining finger 20 is provided which is arranged to engage one side of the loop of needle thread as the looper moves transversely, and to spread and retain this loop in proper position for the passage of the upper needle therethrough. The thread retaining finger is preferably arranged to project obliquely from the lower part of the throat plate and across the path of the thread leading from the looper point to the seam when the looper has carried the needle loop forward and is about to move transversely. The looper point 16 is provided

with a thread guide and thread eye through which an under thread is threaded. This looper acts to carry a loop of under thread through a loop of needle thread, and this 5 loop of under thread is spread for the passage of the needle therethrough by a spreader point 22 mounted to move with and enter the loop with the looper point, and then to move transversely to spread the loop 10 of under thread.

In the preferred construction shown, the looper point 16 is secured in the arm of an oscillating support or carrier 24, and the transversely movable looper point 18 and 15 spreader point 22 are secured in the arms of a carrier lever 26 which is mounted on the oscillating support 24 to move about an axis substantially at right angles to the axis of the support. The support 24 is provided 20 with two separated bearings 28 mounted to turn on the inner ends of studs 30 which are secured in lugs projecting from the upper edge of the turret 12. The support is oscillated through a link comprising a tubular 25 part 32, to the upper end of which is secured an arm 34 connected to the support. The lower end of the link is connected by a ball joint with the forward end of a lever 36, which is rocked to oscillate the support by a 30 three-cornered eccentric 38 secured to the sewing shaft 40, and engaging a fork 42 on the upper end of a link 44, the lower end of which is connected to the rear end of the lever. The carrier lever 26 is mounted on a 35 pivot 46 arranged on the support 24 between and at right angles to the pivot studs 30. The lever is provided with a horizontal arm 48 arranged substantially in the axis of the support 24, and having its outer end connected by a ball and socket joint to the upper end of an arm 50, the lower end of which is secured to the upper end of a tube 52 which extends down through the tube 32, and is connected at its lower end by a ball 40 joint to the forward end of a lever 54. The lever 54 is rocked to oscillate the carrier 26 by an eccentric 56 on the needle shaft 58 which engages the upper end of a link 60, the lower end of which is connected to the 45 lever. Since the needle shaft 58 is geared to make two revolutions for each revolution of the sewing shaft 40, the carrier 26 will be oscillated during the movement of the support 24 in each direction to impart trans- 50 verse movements to both the looper point 18 and the spreader point 22.

The mode of operation of the sewing mechanism in forming the overseam stitches is illustrated in Figs. 5 to 15. During the 55 depth stroke of the needle the support 24 is rocked toward the left to pass the end of the looper point 18 through a needle loop. The forward movement of the looper point carries this loop to the left into the position indicated in Fig. 5. During the final move-

ment of the looper point toward the left, the needle thread leading from the end of the looper point to the seam is brought in front of the thread retaining finger 20, and the carrier lever 26 is rocked to move the 70 looper point transversely across the needle path. During this transverse movement of the looper point the seam side of the needle loop is held or retained by the retainer finger, so that the loop of needle thread is adequately spread and retained in position to insure the passage of the needle therethrough during its next slit stroke, as indicated in Fig. 6. When the looper point is withdrawn from the needle loop the loop 80 readily disengages itself from the retaining finger, so that it may be drawn into final position in the seam. After the needle has entered the loop of thread, the support 24 is rocked toward the right, and at the same 85 time the carrier lever 26 is rocked on its pivot to bring the spreader point 22 over the threaded looper 16 and into position to pass through the needle loop with the looper point, as shown in Figs. 9 and 10. During 90 the continued movement of the support toward the right, the looper point 16 and spreader point 22 are passed through the needle loop, the position of the points as they enter the needle loop being indicated in 95 Figs. 11 and 12. During the final movement of the looper and spreader points toward the right, the carrier lever 26 is rocked to move the spreader point transversely of the direction of travel of the looper to spread the loop 100 of under thread and present it in position for the passage of the needle therethrough during its next depth stroke, as indicated in Figs. 13 and 14. The support 24 is then again rocked toward the left, and during the 105 first part of the movement the carrier lever 26 is rocked on its pivot to return the spreader point into position over the looper point 16, and to return the looper point 18 into position to again pass through a needle loop thrown out by the needle in its 110 depth stroke.

The mechanism for vibrating or jogging the needle 14 comprises a vertically reciprocating and laterally vibrating carrier sleeve 115 62 within which the needle bar 64 reciprocates. The carrier sleeve is reciprocated vertically through a bell crank lever 66, the horizontal arm of which is connected by a ball joint with the upper end of the sleeve, and the vertical arm of which is connected 120 by a link 68 with an eccentric on the sewing shaft 40. The lower end of the sleeve is moved laterally by a link 70, one end of which is connected to the sleeve, and the other end of which is connected with a pivot 72 on a rotary head 74. When the sleeve is moved downward the link acts to swing the lower end of the sleeve and the needle bar toward the right, so that the needle bar will 130

be positioned for the depth stitch. When the sleeve is raised, the link acts to swing the sleeve toward the left, so that the needle bar will be positioned to form the slit or edge stitch. The needle bar is reciprocated by a crank 76 on the needle shaft which is connected to the needle bar by a link 78. Since the needle shaft makes two revolutions for each revolution of the sewing shaft, the needle carrier will be moved to the right during one reciprocation of the needle, and to the left during the succeeding reciprocation, so that the needle will be vibrated or jogged to alternately form the 15 depth and edge or slit stitches.

The rotary head 74 in which the carrier sleeve and needle bar are carried, and the rotary turret 12 in which the looper mechanism is carried, are rotated in unison during 20 the sewing about the eye of a buttonhole through shafts 80 and 82 geared to the head and turret, and operated by connected gear segment levers 84 and 86, one of which is provided with an arm carrying a roll engaged by a cam on the cam shaft of the machine.

While the invention has been shown and described as embodied in a machine for sewing a two-thread overseam, and in which 30 the upper thread is carried by a transversely vibrating needle, and in which the sewing mechanism is mounted to rotate during the sewing, it will be understood that the invention is not confined in its application to such a machine, but may be embodied with advantage in other types of machines. It will also be understood that the invention is not limited to the specific construction and arrangement of parts shown 35 and described, but may be embodied in other constructions, the specific construction and arrangement of parts being varied or modified as found desirable or best suited to the machine or mechanism in which the invention is to be embodied.

Having explained the nature and object of the invention, and specifically described one form of mechanism in which it may be embodied, what is claimed is:—

50 1. A sewing machine, having, in combination, upper needle mechanism above the work, a reciprocating and transversely moving looper point below the work for taking and carrying a needle loop, a thread retainer to which the loop is carried by the

looper and coöperating therewith to spread the loop of needle thread, an opposed and alternately acting threaded looper, and a spreader point moving with and transversely of the threaded looper.

60

2. A sewing machine, having, in combination, an upper needle mechanism above the work, a reciprocating support below the work, a threaded and an opposed unthreaded looper carried on the support, a loop spreader point coöperating with the threaded looper, a thread retainer to which a needle loop is carried by the unthreaded looper and coöperating with the looper to spread the needle loop, and mechanism for 70 moving the unthreaded looper and spreader point transversely.

65

3. A sewing machine, having, in combination, a reciprocating and laterally jogging upper needle, two opposed looper points below the work, one of which is threaded, mechanism for reciprocating the looper points and for moving the unthreaded looper transversely across the needle path, a thread retainer to which the loop of 75 needle thread is carried by the unthreaded looper, and a spreader point moving with and transversely of the threaded looper.

75

4. A sewing machine, having, in combination, an upper needle mechanism above the work, a reciprocating support below the work, a carrier mounted to move with and transversely of the support, a threaded looper on the support, a coöperating spreader point and an opposed unthreaded looper on the carrier, and a stationary thread retaining finger for coöperating with the unthreaded looper to spread a needle loop.

80

5. A sewing machine, having, in combination, an upper needle mechanism above the work, an oscillating support below the work, a carrier mounted on the support to oscillate about an axis substantially at right angles to the axis of the support, a threaded looper point on the oscillating support, a coöperating loop spreader point and an opposed unthreaded looper point on the carrier, mechanism for oscillating the support and for oscillating the carrier on the support at twice the speed, and a stationary thread retainer finger coöperating with the unthreaded looper point to spread a needle loop.
